UNITED STATES PATENT OFFICE.

THOMAS SINGLETON, JR., OF NEW BEDFORD, MASSACHUSETTS, ASSIGNOR TO
THE MOUNT WASHINGTON GLASS COMPANY, OF SAME PLACE.

DESIGN FOR A GLASS VESSEL.

SPECIFICATION forming part of Design No. 23,496, dated July 24, 1894.

Application filed March 17, 1894. Serial No. 504,105. Term of patent 7 years.

To all whom it may concern:

Be it known that I, THOMAS SINGLETON, Jr., of New Bedford, in the county of Bristol and State of Massachusetts, have invented and 5 produced a new and original Design for a Glass Vessel, of which the following is a specification, reference being had to the accompanying drawing showings, the same.

Figure 1 is a bottom plan view, and Fig. 2 a central sectional view of a dish embodying my design.

The leading feature of my design consists of a raised polygonal base, at each polygonal side of which is the lower portion of a curved 5 groove extending from said polygonal side upwardly in both directions toward the margin of the dish, there being as many of such curved grooves as there are sides of the polygonal base, and each end of each curved 10 groove crossing an end of a curved groove on a diamond-shaped ornament, the two longer

sides of which extend upwardly to the rim of the dish and are contiguous to fan ornaments alternating with the diamond-shaped ornaments around the margin of the dish. 25

In the drawings, A is the polygonal base, and a the sides thereof.

B is a series of curved grooves, the lower portions b of which are each contiguous to a side a of the base. These curved grooves B 30 intersect one another at b' at the base, of a diamond shaped ornament D, the diamond-shaped ornaments D, alternating with the fan ornaments F around the margin of the dish. Base A is preferably ornamented with a ro- 35 sette A'.

What I claim is—

The design for a glass vessel herein set forth.

THOMAS SINGLETON, JR.
